Francis H. McCormick,

by *Alexander S. Kent*,
His Attorney.

UNITED STATES PATENT OFFICE.

FRANCIS H. McCORMICK, OF GLEN ELLYN, ILLINOIS, ASSIGNOR TO EDISON ELECTRIC APPLIANCE COMPANY, OF CHICAGO, ILLINOIS, A CORPORATION OF NEW YORK.

ELECTRIC HEATER.

Application filed October 1, 1927. Serial No. 223,424.

My invention relates to electric heaters, more particularly to electric heaters of the radiant type, and has for its object the provision of a simple and reliable heater of this character.

In carrying out my invention, I provide a support for the heating resistor comprising a plurality of elongated heat refractory members provided with overhanging projections. These members are assembled in alternate relation to form a support so that the projections point in opposite directions in zig-zag relation and secure a heating resistor which extends between them.

For a more complete understanding of my invention, reference should be had to the accompanying drawing in which Fig. 1 is a plan view of an electric heater embodying my invention; Fig. 2 is a fragmentary elevation view of the device shown in Fig. 1; Fig. 3 is a sectional view along the line 3—3 of Fig. 2 looking in the direction of the arrows; while Fig. 4 is a fragmentary perspective view showing the supporting members.

Referring to the drawing, I have shown my invention in one form as applied to a wall type radiant heater, i. e., a heater which is arranged to be mounted in an opening or recess provided for it in the wall of a building. As shown the heater comprises an open front metallic casing 10 which is set in an opening in the wall. A metallic supporting bracket is secured in this casing, this bracket comprising a substantially vertical smaller back member 11, which is arranged in spaced relation with the back wall of the casing 10, together with an upper member 12 which is joined to the member 11 at the top and extends from the portion 11 in an upwardly inclined direction to a point substantially flush with the front opening of the casing 10, a ventilating space 13 being provided between the member 12 and the top of the casing. As indicated in Fig. 1, the vertical portion 11 is considerably smaller in width in a horizontal direction, and also in height, than the casing. Side members 14 and 15 are secured to the sides of the member 11, respectively, and extend toward the front of the casing in diverging relation. At their outer edges these side members 14 and 15 are secured to the side walls of the casing by means of brackets

16 and 17. The member 12 is secured at each end to the upper ends of the side members 14 and 15. A bottom member 18 is also provided, this member having a flange at the back by means of which it is secured to the back member 11 and at each end it is flanged and secured to the side members 14 and 15.

The bracket thus formed in the casing provides a support for an electric heating unit. This heating unit comprises a support formed from a plurality of elongated electrically insulating blocks 19 stacked horizontally upon each other and provided with curved sides which are placed toward the front of the casing, as indicated in Fig. 1. These blocks are stacked on the bottom member 18 and clamped between the bottom member and a flange 20 on the upper end of the back member 11 by means of a bolt 21 which passes through central apertures in the blocks. The blocks are identical in construction and are preferably molded from heat refractory electrically insulating material. They are each provided with a plurality of hooks in their front curved sides. It will be observed that these hooks are formed by making suitable recesses 22 in a rib 23 which extends lengthwise on the curved front side of the block and centrally thereof, these recesses being provided with overhanging side walls 24 pointing toward the same end of the block. Between the recesses forming the hooks are strengthening ribs 25. The recesses, furthermore, are equally spaced and the series of recesses begins nearer one end of the block than the other, whereby the blocks may be stacked in alternate or reverse relation so that the hooks point in opposite directions and are in zig-zag relation in a transverse direction. A helical resistance conductor 26 is threaded up and down through these series of zigzag recesses in a plurality of vertically extending lengths each of which extends in a zigzag manner across the support.

In order to further secure the blocks they are each provided at one end with a transverse aperture 27 and at the other end with projections or protuberances 28 and 29 on opposite sides. These holes and protuberances are spaced equal distances from the central aperture 30 for the bolt 21 so that when the blocks are stacked in reversed

relation the blocks are interlocked at their ends by the protuberances fitting in the apertures 27, as will be understood from an examination of Fig. 4. Preferably, a bottom block 31 of special form is provided, this block being provided with projections 32 extending downward through apertures provided for them in the base member 18. Apertures are provided in the block 31 for the terminal leads 33 connected to the ends of the heating resistor, the apertures extending through the projections 32 which thereby constitute insulating sleeves for the terminal leads. The terminal leads are connected to a control switch 34 which is mounted on a front plate 35 and secured at its corners by bolts 36 to the casing 10. The switch is provided with an operating lever 37 which projects through an aperture in the plate 35 whereby the switch may be operated from the front of the plate.

The plate 35 is provided with ventilating apertures 38 at the bottom which communicate with the space formed between the bottom member 18 and the bottom of the casing whereby air is free to enter through these apertures and flow upward between the back member 11 and the casing to the space 13 where it flows out through a series of apertures 39 provided in the front plate. This provides for a circulation of cooling air around the back, top, bottom and sides of the bracket supporting the heating unit whereby the casing 10 is maintained at a sufficiently low temperature to prevent any fire hazard. A baffle plate 40 is preferably secured to the back wall of the casing in spaced relation therewith and also in spaced relation with the back wall 11 of the bracket. In order to still further reduce the operating temperature of the casing, a sheet of heat insulating material 41, such as asbestos, is secured to the top member 12 of the bracket on its top or inner side and also a similar sheet 45 of insulating material 42 is secured to the inside of the casing at the top thereof.

The front plate 35 is, furthermore, provided with a plurality of apertures 43 in a central portion 44 just in front of the heating unit, this central portion 44 having substantially the same area as the front opening of the supporting bracket for the heating unit. This central portion extended outward and, as shown, is formed as a separate member which is secured to the front plate in an opening therein provided for it. The front plate and portion 44 thus constitute a grating covering the front of the casing.

While I have described my invention as embodied in concrete form and as operating in a specific manner in accordance with the provisions of the patent statutes, it should be understood that I do not limit my invention thereto since various modifications thereof will suggest themselves to those

skilled in the art without departing from the spirit of my invention, the scope of which is set forth in the annexed claims.

What I claim as new and desire to secure by Letters Patent of the United States, is,—

1. An electric heater comprising a plurality of elongated heat refractory members provided with overhanging projections pointing lengthwise thereof, said members being arranged in reversed relation, and a heating resistor secured by said projections extending in a zigzag path transversely of said members.

2. An electric heater comprising a plurality of elongated heat refractory members, a rib on each of said members extending lengthwise thereof, said rib being provided with recesses having overhanging walls and said members being arranged side by side with said recesses in zigzag relation, and a resistance conductor extending crosswise of said members in zigzag relation between said recesses.

3. An electric heater comprising a plurality of elongated heat refractory members provided with overhanging projections pointing lengthwise thereof, said members being arranged in reversed relation, a heating resistor secured by said projections extending in a zigzag path transversely of said members, an open front casing, a bracket secured to said casing on which said members are secured in spaced relation to the top, bottom and back walls of said casing so as to provide for the circulation of cooling air between said support and said casing, and a grating over the front of said casing.

4. An electric heater comprising a support formed from a plurality of elongated heat refractory members provided with a projection on each side at one end and an aperture in the opposite end, said members being stacked in reversed relation so that the projections on one member fit in the apertures in the two adjoining members, a rib on each of said members extending lengthwise thereof, said rib being provided with equally spaced recesses having overhanging walls pointing toward one end of said member and said recesses being nearer one end of said member than the other, whereby said overhanging walls in the assembled support point in opposite directions and are in staggered relation in a transverse direction, and a resistance conductor extending across said members and secured by said overhanging walls.

5. An electric heater comprising a support formed from a plurality of elongated heat refractory members provided with a projection on each side at one end and an aperture in the opposite end, said members being stacked in reversed relation so that the projections on one member fit in the apertures in the two adjoining members, a rib on each

of said members extending lengthwise thereof, said rib being provided with equally spaced recesses having overhanging walls pointing toward one end of said member,
5 said recesses being nearer one end of said member than the other whereby said overhanging walls in the assembled support point in opposite directions and are in staggered relation in a transverse direction, a
10 resistance conductor extending across said members and secured by said overhanging

walls, an open front casing, a bracket secured to said casing on which said support is mounted in spaced relation to the top, bottom and back walls of said casing so as to provide for the circulation of cooling air between said support and said casing, and a grating over the front of said casing.

In witness whereof, I have hereunto set my hand this 26th day of September, 1927.

FRANCIS H. McCORMICK.
